LIQUID PUMPING AND CIRCULATING SYSTEM

Charles Lawrence Stokes, Los Angeles, Calif.

Application November 10, 1924, Serial No. 748,932

8 Claims. (Cl. 123—137)

My invention relates to improvements in liquid circulating and pumping systems wherein the waste heat of an internal combustion engine is utilized for circulating or transferring a liquid.

5 The principal object of my invention is to provide a closed circulatory system wherein a fluid is repeatedly vaporized and condensed, the vaporizing being done by the waste heat in the fuel supply to an internal combustion engine, and the 10 condensing being done by the fuel being supplied to the same engine.

A further object of my invention is to provide a vaporizing chamber for an internal combustion engine wherein steam, or superheated steam, is 15 continually circulated and condensed by the transfer of its latent heat to a volatile fuel in indirect contact with the steam in the vaporizing chamber.

20 A further object of my invention is to provide a reciprocating condenser which acts as a pump and a condenser.

A further object of my invention is to provide a simple liquid pump having a minimum number of working parts.

25 Referring to the drawing, in which the same numbers indicate like parts:—

Fig. 1 is a view of an engine showing my invention in operative relation thereto.

Fig. 2 is a vertical section of the vaporizing 30 chamber shown in Fig. 1.

Fig. 3 is a transverse section along the lines 3—3 of Fig. 2.

Fig. 4 is a diagram showing my invention applied to pumping systems for internal combustion engines.

Fig. 5 is a vertical section in part view of part of Fig. 4.

Fig. 6 is an alternative construction of Fig. 5.

40 Fig. 7 is an alternative construction of Fig. 5. It is considered highly desirable in modern gas engine practice to provide some method of vaporizing the gasoline being supplied to the engine and in general the methods provided include the use of the waste heat in the engine exhaust gases

45 which is generally supplied to a so-called "hot spot", the exhaust gases being often diverted from the main exhaust pipe to the "hot spot". Any diversion of gases through conduits invariably causes condensation therein of carbon and lubricating oil vapors whereby such conduits become choked in a comparatively short time and cannot function as desired. A hot air pipe is also provided as a rule which has the defect of raising the temperature of the air supplied to the engine 55 as well as partly vaporizing the fuel.

These defects I am now enabled to overcome by providing a steam circulatory system through a "hot spot" wherein the latent heat in the steam is transferred principally to the volatile fuel being supplied to the engine and the steam thereby

condensed is circulated, reheated and condensed in cyclic fashion.

In Fig. 1 an internal combustion engine 1 is provided with an exhaust pipe 2, an inlet manifold 3 and a carburetor 4. Between the carburetor 4 and the intake manifold 3 is placed a steam vaporizing "hot spot" 5 which is joined at its upper end by a pipe 6 to the upper end of a steam chamber 7, the lower end of 7 being joined by a pipe 8 to the lower end of 5.

70 The carburetor 4 is supplied with air through a port 9 and with liquid fuel through a pipe 10, the discharge of air and liquid fuel from 4 being controlled by a throttle 11. The position of throttle 11 when closed will govern the discharge 75 of an idling mixture of liquid fuel and air supplied through a pipe 12.

Referring to Figs. 2 and 3 it will be seen that the manifold 3 is expanded slightly at its base to be joined by the flanged upper end of 5 which 80 consists of a tubular chamber through which is passed a plurality of thin walled metal tubes 13, the combined areas of which preferably slightly exceed the area of discharge of the inlet manifold 3 or carburetor 4.

85 The tubes 13 therefore provide a passage for air and liquid fuel through their interiors from 4 to 3 and exteriorly the tubes 13 are subjected to the heat supplied by the vaporization of water in 7 passing through pipe 6 to the upper end of 5. 90 The steam condensing in 5 is withdrawn at its lower end, which is preferably slanted as shown, through the pipe 8 which reconveys the condensed water to the lower end of 7.

95 The chamber 7 is encased, or subjected to the heat of the exhaust gases, in the exhaust pipe 2 and contains a predetermined quantity of a liquid such as distilled water, methyl alcohol, ethyl alcohol, or many other liquids are suitable for my purposes. In general however I 100 prefer to use distilled water in 7 because the characteristics of the same when subject to heat do not vary the world over.

A port 14 is provided in the upper end of 5, being tightly closed normally by a plug 15 to 105 the end that the system comprising 5, 6, 7, and 8 will constitute a closed circulatory system.

The operation of the system described is that upon cranking the engine 1, the throttle 11 will be very slightly open in the direction of the 110 arrow shown in Fig. 2 whereupon the engine induction vacuum will cause an idling mixture of air and liquid fuel from 12 to be drawn upwardly and through the tubes 13 closest to the wall through which fuel and air is supplied and also 115 closest to the wall to which 6 is joined.

If it be assumed that in extremely cold weather and any water in 7 is frozen, the quantity of water therein is in general so small that the first few 120 explosions of the engine conveys sufficient heat

through 2 to melt the same and rapidly convert the same to steam. The steam then passes through the pipe 6, which may be relatively large when compared to 8 and is suitably insulated against heat losses, to the interior of 5 where it impinges against the tubes 13 through which the idling mixture from 12 is passing thereby heating the same and transferring its heat through the thin metal walls of tubes 13 to the film of liquid fuel being drawn along the interior walls of 13 and the transfer of said heat causes the condensation of the steam to water which then falls to the bottom of 5 and is retransferred through 8 to the interior of the bottom of 7 where it is revaporized and again passes through the system.

It should be understood of course that the circulation of steam and recirculation of condensed water through the system described is continuous as long as the engine 1 is operated so that, inasmuch as a higher heat is conveyed to 7 through the pipe 2 at higher engine speeds, the circulation of steam continues at a higher rate according as the throttle 11 is more fully open. Thus, automatically, the application of heat by the steam to the tubes 13 is provided in increasing quantity according to the increased demands of the engine 1.

In order to provide maximum efficiency for the circulatory system whereby the water in 7 will be quickly vaporized with a minimum application of heat thereto, the pipe 6 made in coil form as shown in Fig. 5 and part of the same may be placed in the interior of 2, whereby the steam generated in 7 is superheated prior to its entry into 5. Another feature for providing the same maximum efficiency is that primarily upon starting the system, the plug 15 is removed and the system is brought to a sufficient temperature to fill the same with steam thereby expelling all air and other gases contained therein. As soon as steam issues from 14, the plug 15 is reinserted for preventing the ingress of air to the interior of 5. Thus after the system is cooled down, a predetermined partial vacuum will prevail therein to the end that the water, or other liquid, in 7 will boil at a predetermined low temperature, lower than normal.

The temperature of exhaust gases as a rule varies from 400° F. to about 1400° F. and thus it will be seen that ample temperature conditions are provided for ensuring the operation of this system under all conditions, more particularly if it is preferred to operate the system initially under vacuum as described.

A similar circulatory system is provided as illustrated in Fig. 4 wherein the carburetor 4 is provided with liquid fuel through the pipe 10 from a liquid fuel reservoir 16 placed at a lower level than 4. In this case a pump chamber 17 is connected at its upper end to the pipe 10 and a pipe 18 serves to convey liquid fuel from 16 through the upper end of 17 to the interior of a reciprocating metal bellows, or expandible member 19 which member is securely held to the cover 20 enclosing the upper end of 17 and the pipe 18 extends through 20 to the lower portion of the interior of 19 for a purpose to be herinafter described.

A check valve 21 is placed in 18 for permitting the passage of liquid fuel solely from 16 to the interior of 19 and a check valve 22 is placed in 19 for permitting the passage of liquid fuel solely from 19 to 4 and a by-pass pipe 22a connects 10

with the pipe 18 on the side of 21 nearest the reservoir 16. A regulating check valve 23 is placed in 22a in order to maintain a predetermined discharge pressure of liquid fuel passing from the interior of 19 through 10 to the carburetor 4, and check valve 23 is arranged to permit any liquid fuel due to excessive pressure to be by-passed from 10 to 18.

A priming plug 23a is provided for filling the interior of 19 at starting with liquid fuel, the lower end of 19 being securely closed by a tapered plug 24 arranged to seat in the lower end 25 of 17 which is also tapered and provided with a boss 26. 24 is centrally drilled at 27 to slidably receive the pipe 8, a small annular space being provided therebetween and the passage 27 communicates through a plurality of passages 28 to the interior of 17. A plug 15 is provided for the same purpose of placing the system under vacuum as already described.

Referring particularly to Figs. 4 and 5, if it be assumed that the system is cold, the apparatus will be in position illustrated in Fig. 5 wherein 24 will be seated in 25, the bellows 19 being expanded due to the vacuum in the system, the interior of 19 being filled with liquid fuel. A predetermined quantity of water is contained in 7, which quantity of water is such as not to fill 25 beyond the upper level of the pipe 8 when 19 is fully compressed.

Upon starting the engine, the heat of the exhaust gases in 2 is transferred to the water in 7 thereby increasing the pressure on the absolute scale in 17 thereby causing 19 to first of all assume a normal position and thereafter to be compressed thus forcing liquid fuel from the interior of 19 through 10 to the carburetor 4, any excess fuel being by-passed through 22a and 23 to 18. The pressure caused by the steam passing from 7 through 6 to the interior of 17 will gradually reach a maximum whereby 19 will reach a maximum compression but this maximum pressure of steam is then rapidly reduced due to the condensation effects of the cool walls of 19 whereupon the condensed water will collect in the lower end of 25 and the bellows 19 will then start to expand thus drawing in a fresh supply of liquid fuel from 16 through 18 and 21 and said supply of fresh liquid fuel, being cool, is directed from the pipe 18 to the lower end of the interior of 19 for circulating the cool liquid through the bellows and impinging the same upon the interior side of 24, it being understood that during the expansion of 19, the check valves 22 and 23 will be closed while the check valve 21 will be open.

The expansion of 19 will thus cause the condensed water in the lower part of 25 to be forced upwardly therein away from the pipe 8 until the same enters the passages 28 and the water is thus admitted to the interior of 8 in a substantially good quantity to the end that said quantity will reach the chamber 7 without being converted to steam, but upon reaching 7, the same is flashed into steam due to the heat of 7 and the cycle is then repeated.

It should be understood that while the steam is preferably superheated for application to the systems described with reference to Figs. 1, 2 and 3. It is not necessary to superheat said steam when used in connection with the system described for Figs. 4, 5, 6 and 7, but the same may be superheated depending upon the length of pipe 10 in order to maintain the water in the form of steam for a comparatively long travel. In

the pumping system just described in Figs. 4 and 5 it will be understood that the circulatory system is intermittent in order to obtain the desired reciprocating action for 19 and therefore the water originally supplied to 7 will be of a definite predetermined quantity so that after one vaporization thereof, the condensed water will be able to be held in 25 without discharge therefrom until injected into 7 through 8 by the expansion of 19.

Referring to Fig. 6 a similar intermittent pumping action as described takes place the essential difference in construction being that the pipe 8 is arranged to directly enter the upper end of 7 and the pipe 10 may be eliminated. Also, the tapered plug 24 is solid being arranged to seat in 25 and inject water through an orifice 29 in the boss 26. In this manner it will be seen that upon vaporizing the water in 7, the steam will pass through 8 and 29 to cause a compression of 19 and the water thereafter condensed in 17 will be maintained therein until a maximum steam pressure is reached and thereafter the condensed water will be ejected as a stream through the orifice 29 directly into 7, the pipe 8 being of comparatively large diameter. The construction shown in Fig. 6 is practically that of a reflux condenser wherein the reflux is restrained from revaporization until a predetermined period has passed for giving intermittent reciprocatory action to 19.

Referring to Fig. 7 a similar intermittent action is obtained by making plug 24 as a disc and attaching thereto a valve 30 for closing the orifice 29, 30 being connected to 24 on a swivelled joint 31 by means of a stem 32 containing an upper stop 33 and a lower stop 34. Between the stops 33 and 34 is held a spring 35 which is pivoted at each end on 17 and is preferably in part corrugated for the purpose of providing a "kick" action to the valve 30 at predetermined positions of 19, whereby a similar action as already described takes place, it being understood that the pipe 8 in the present case also extends directly into the upper end of 7 and is of comparatively large diameter.

The action of the "kick" spring 35 is well understood and many equivalents therefore are available and adaptable for a similar purpose.

In case accentuated condensing effect is desired in 17, the same may be made of aluminum having thereon a series of radiating fins 35a, which fins may also if desired extend interiorly of 17.

It will be of course obvious that the circulating and pumping system is applicable for pumping of any description such as gasoline, oil, or water and may be applied to liquid pumping systems generally, and that any suitable means may be employed for supplying heat necessary to operate the device.

I claim:

1. The method of transferring heat from one part to another in a fluid circulatory system for internal combustion engines being supplied with liquid fuel which consists in applying the engine heat to a self-contained circulatory system and vaporizing liquid therein, passing the vaporized liquid along one path to a cooler part of the engine and transferring the latent heat of the liquid to the liquid fuel whereby the vapors of the liquid are condensed, utilizing the expansive force of said volatized liquid for causing a flow of liquid fuel in proximity to said volatized liquid, then returning the first-named liquid through another

path for further vaporization, the vaporizing, circulating and condensing being conducted at a lower temperature than that required to boil the liquid fuel at normal atmospheric pressure.

2. In combination, a casing comprising a receptacle for holding liquid fuel, an internal combustion engine, a fuel passage through said casing, a boiler, a pair of conduits connecting said casing to said boiler for forming a closed circuit, a fluid in said circuit, means for continuously heating said boiler for vaporizing said fluid, said fluid being condensed by coming in contact with the walls of said passage within said casing and being automatically returned to said boiler to be revaporized and means for discharging said fuel from said receptacle, said means being operated by the expansive force of the vaporized fluid. 80

3. In combination, an exhaust pipe, a boiler associated with said pipe and adapted to contain a fluid, a casing, a pump within said casing, passages leading into and out of said pump through which liquid fuel is adapted to pass, and a passage from said boiler to said casing for conveying a fluid from said boiler to said casing for heating said liquid fuel and for operating said pump and a second passage for returning said fluid to said boiler. 90

4. A method of heating liquid fuel for an internal combustion engine which consists in vaporizing a liquid, transferring the same along one path into close proximity to said liquid fuel while the same is in a passive state for heating the same, utilizing the expansive force of said liquid when vaporized for causing a flow of said fuel and condensing said liquid, and returning the 100 condensed liquid along another path to be re-vaporized. 105

5. In combination, an internal combustion engine, a casing, pump mechanism within said casing, a vaporizer, means for conducting a vaporized fluid to said casing through one conduit for operating said mechanism, and means for automatically returning the condensed fluid to said vaporizer along another conduit. 115

6. In combination, an internal combustion engine, a carburetor therefor, means including a pump for supplying fuel to said carburetor, and a closed fluid circulating system heated by the exhaust from said engine for operating said pump, said system comprising a plurality of conduits for conducting said fluid to and from said pump. 120

7. In combination, an internal combustion engine, a carburetor therefor, means including a pump for supplying fuel to said carburetor, and a fluid circulating system heated by the exhaust from said engine for operating said pump and for heating said fuel as the same passes through said pump, said pump having separate intake and discharge conduits and said system having 130 independent direct and return passages for conducting said fluid to and from said first named means.

8. In combination, an internal combustion engine, a carburetor for supplying fuel to said engine, a pump, a self-contained closed circulating system comprising a plurality of independent passages for containing a liquid and vapor thereof and means for converting the liquid in said circulating system into a vaporized fluid for operating said pump for supplying fuel to said carburetor, said system having a plurality of conduits for conducting fluid to and from said pump. 140

CHARLES LAWRENCE STOKES.
